UNITED STATES PATENT OFFICE.

ALBERT C. GRUNWALD, OF CHICAGO, ILLINOIS, ASSIGNOR TO PRECISION METAL WORKERS, OF CHICAGO, ILLINOIS, A CORPORATION OF ILLINOIS.

GREASE-CUP.

1,227,131.

Specification of Letters Patent.

Patented May 22, 1917.

Application filed November 14, 1916. Serial No. 131,194.

To all whom it may concern:

Be it known that I, ALBERT C. GRUNWALD, a citizen of the United States, residing at Chicago, in the county of Cook and State of Illinois, have invented a new and useful Improvement in Grease-Cups, of which the following is a specification.

This invention relates, more particularly, to grease-cups equipped with agitators or feed devices.

The invention may be applied either to a stationary journal-box or to a movable journal-box, for instance, the invention may be applied to the stationary journal-box of an engine shaft, or to the movable journal-box of the connecting rod. In either case, the device operates successfully owing to the normal vibration or jar which is incidental to the operation of the machine.

The present invention is in the nature of a modification of the invention set forth in my application No. 131,193, filed of even date herewith.

The primary object of the present invention is to provide a simple and desirable form of connection between the grease-cup and its cap, whereby the cap may be securely locked to the grease-cup and still be capable of being detached from the grease-cup with the greatest facility.

In the accompanying drawing, the invention is shown applied to a stationary bearing, but it will be understood that it may be applied to a movable bearing, as, for instance, to the journal-box of the connecting rod. In the construction illustrated—

Figure 1 represents a broken vertical sectional view of bearing equipped with the improved grease-cup; Fig. 2, a perspective view showing the grease-cup brokenly and the cap detached from the grease-cup; Fig. 3, an enlarged broken horizontal sectional view taken as indicated in line 3 of Fig. 1; Fig. 4, a broken sectional view showing a modification of the grease-cup cap; and Fig. 5, an inner view of the cap shown in Fig. 4.

In the construction illustrated, A represents a journal-box; B, the journal of a shaft; C, a grease-cup equipped with a cap C¹; and D, an agitator or feed device mounted in the grease-cup and having a stem extending through an opening 1 in the upper

wall of the journal-box and resting upon the journal B.

The grease-cup C has a nipple provided with a threaded portion 2 and with a hexagonal portion 2^a. The upper portion of a passage 1 is countersunk and tapped and the nipple 2 is screwed therein. A retainer 3 serves to prevent unscrewing of the grease-cup, said retainer having a hexagonal perforation receiving the hexagon 2^a and having arms engaging the journal-box.

The cap C¹ is provided with a downturned flange which has bayonet-joint connections with the upper portion of the grease-cup C. These connections may be provided by striking the metal of the cup outwardly near the upper edge of the cup to form diametrically opposite studs or embossments 4, and by striking the metal of the flange of the cap C¹ outwardly at diametrically opposite points to provide bayonet-slots 5. The bayonet-slots 5 are provided with offsets 5^a whose lower walls afford shoulders which the studs 4 engage in the locked condition of the cap.

Adjacent one of the studs 4, the metal of the cup is struck inwardly to form a vertical depression 6 which accommodates a leaf-spring 7 whose lower end is secured by means of a rivet 8. The main body-portion of the spring 7 is struck outwardly so that the spring projects normally a little beyond the outer surface of the cup, the upper end of the spring being bent inwardly or beveled as indicated at 7^a, so that the flange of the cap C¹ will engage and depress the spring when the cap is placed on the cup.

In applying the cap to the cup, the cap is turned so that the studs 4 will enter the lower ends of the bayonet-slots, after which the cap is turned to cause the lower walls of the offsets 5^a of the slots to engage the studs as shown in Fig. 3, thus locking the cap to the cup. After such rotation, the spring 7 engages the bayonet-slot in the flange of the cap as shown in Fig. 3, so that the cap cannot be turned in the reverse direction until the spring 7 is depressed, as by placing the thumb upon it. Thus the spring associated with the grease-cup and its cap serves effectively to maintain the bayonet-joint connections in interlocked relation, so that the cap is securely held upon the grease-cup.

The agitator D comprises a rod 9 equipped with a conical member or feed head 10; and a light coil spring 11 encircling the rod 9 and interposed between the cap C¹ and the member 10. The upper end of the rod 9 protrudes through a central opening in the cap C¹ which thus serves as a guide.

In the modification shown in Figs. 4 and 5, the construction is the same as described except that the cap C² is of modified form. In this case, the cap is provided with an upwardly struck central portion or hollow embossment, 12, which serves as a housing for the upper end of the rod 9. Across the open lower end of the embossment 12 extends a metal plate 13 whose ends are riveted to the cap and which has a central perforation which affords a guide for the rod 9. The bayonet-joint connections and the locking spring 7 are the same as in the previously described construction. The spring 11, in this case, bears at its upper end against the guide plate 13.

Certain of the features of construction herein illustrated are fully described and claimed in the co-pending application mentioned above, and need not be further described herein.

In the use of the improved device, the normal vibration or jar incident to the operation of any engine or machine suffices to move the agitator D. The spring confined between the cap and the enlargement on the agitator serves to return the agitator repeatedly to its bearing on the journal B, and prevents the agitator from being wedged or held upwardly by grease settling between the cone 10 and the contracted walls of the lower end of the grease-cup.

The bayonet joint and locking spring disclosed herein are simple, cheap and thoroughly effective for the purpose. The cap may be removed with the greatest facility from the grease-cup, as occasion may require.

The foregoing detailed description has been given for clearness of understanding only, and no necessary limitation should be understood therefrom, but the appended

claims should be construed as broadly as 50 permissible in view of my application referred to above.

What I regard as new and desire to secure by Letters Patent is:—

1. In a device of the character set forth, 55 the combination of a grease-cup, a cap provided with a down-turned flange having bayonet-joint connections with the upper portion of said grease-cup, and a spring adapted to interlock between said cup and 60 the flange of said cap and thereby maintain said bayonet-joint connections in interlocked relation.

2. In a device of the character set forth, 65 the combination of a grease-cup equipped externally with a vertically disposed spring, and a cap provided with a down-turned flange having bayonet-joint connections with the upper portion of said grease-cup, the flange of said cap having a shoulder 70 adapted to interlockingly engage said spring and maintain said bayonet-joint connections in interlocked relation.

3. In a device of the character set forth, 75 the combination of a grease-cup equipped with a laterally projecting stud and adjacent thereto with a depression in the external surface of the cup, a spring secured to the cup and adapted to be accommodated by said depression, and a cap provided with a 80 flange having an outwardly-struck wall affording a bayonet-slot, said bayonet-slot adapted to be interlockingly engaged by said spring and having an offset shoulder 85 adapted to interlockingly engage said stud. 85

4. In means of the character set forth, 90 the combination of a grease-cup having a nipple adapted for connection with a journal-box, a cap detachably secured to said grease-cup and having an upwardly-struck central embossment, a guide-member carried by said cap and having a centrally-disposed guide opening, and an agitator in said grease-cup having a rod with its lower end protruding through said nipple and its upper end projecting through said guide-member into said embossment. 95

ALBERT C. GRUNWALD.
